MASSACHUSETTS.

CARBURETER.

1,202,771.

Specification of Letters Patent. Patented Oct. 31, 1916.

Application filed April 8, 1914. Serial No. 836,532.

To all whom it may concern:

Be it known that we, MILES E. BABBITT, a resident of Brookfield, and JAMES F. BEAUMONT, a resident of Worcester, both citizens of the United States, residing in the county of Worcester and Commonwealth of Massachusetts, have jointly invented a new and useful Improvement in Carbureters, of which the following, taken in connection with the accompanying drawings, is a specification.

The present invention relates to the construction of a carbureter, having novel means for applying heat to the constituents of the explosive mixture formed thereby, whereby to facilitate and to render more intimate the commingling of the said constituents. The invention also involves the provision of a mixture heating means acting in conjunction with the first mentioned heating means.

Furthermore the invention aims to provide a carbureter which is equally adaptable to the use of gasoline or kerosene, as fuel, due to its ability to promote the vaporization of the last mentioned hydrocarbon under the most advantageous conditions coincident with its admixture with the air forming the other constituent of the explosive mixture.

Other objects and advantages will appear as the description proceeds.

In the accompanying drawings, the figure is a vertical sectional view of a carbureter constructed in accordance with our invention, the same being shown in connection with a float chamber of any ordinary construction.

The form of carbureter to which our improved heating means in the present instance is applied is similar in construction to the carbureter disclosed in our pending joint application, Serial No. 710,826, filed July 22, 1912. The outer shell of said carbureter is made in two parts, the lower part forming an air chamber 2, provided with the usual main and auxiliary air inlets 3 and 4, respectively, while the upper part 5 forms a chamber 6, which contains the mixing and heating devices of the carbureter and which

is open at its upper end for connection to the inlet manifold, not shown, of an internal combustion engine. The upper part 5 of the shell is detachably secured to a neck portion 7 projecting from the air chamber 2, and within this neck portion 7 is provided an annular shouldered flange 8, adapted to support a ring 9, which is apertured as at 10, for a purpose which will hereinafter appear.

The inner periphery of ring 9 is screw threaded, to receive and support the exteriorly screw threaded hollow annular shell 11, which is closed at both ends to provide an annular fuel chamber 12, communicating by means of the tubular connecting pipe 13 with a float chamber 14, of any desirable type of construction, preferably supported adjacent the carbureter. The inner wall of the shell 11 has leading therefrom, and preferably integral therewith, a short tubular section 15 which communicates with and supports centrally of the shell 11 a vertical tubular section 16, the upper open end of which constitutes a nozzle 17 for the delivery of fuel from the shell. The entrance to the nozzle 17 is beveled to provide a valve seat 18, for co-operating with an adjustable screw threaded needle valve 19, carried within the lower portion of the section 16. The stem of the needle valve passes through a suitable stuffing box 20 on the lower open end of section 16 and extends exteriorly of the carbureter shell, being provided on its end with a suitable knurled adjusting head 21, by means of which the amount of fuel permitted to pass through the nozzle 17 may be delicately regulated.

A hollow annular casing 22 having an upper open end and provided with a depending annular flange in screw threaded engagement with the upper end of the shell 11 is superposed on said shell, in position to surround the end of the nozzle 17. An annular cover plate 23, having an interior depending flange 24 engaging the inner wall of the casing 22, closes the open upper end of the same and provides an annular closed chamber within said casing for the reception of a heating element 25, consisting in the present instance of a number of turns of 100

- high resistance wire, preferably German silver, which are protected and surrounded by a mass of fire clay or porcelain entirely filling said chamber, as shown in the drawing.
- 5 The ends of the coil of wire are connected to leads 26, only one of which is shown, the said leads being carried in tubular projections 27 extending outwardly from casing 22 through the side wall of the upper portion 5 of the carbureter.
- 10 The cover plate 23, above referred to, is preferably formed integral with a cylindrical shell 28, fitting snugly over the exterior of the casing 22 and extending well above the same to support at its upper end a second casing 29 containing an annular chamber for the reception of a heating element 30 identical with that described in connection with the casing 22. The leads 31 to the 15 coil of wire in said chamber are carried in tubular projections 32 extending through the carbureter shell, in the same manner as in the other heating element 25. The casing 29, which is held in spaced relation to the shell 28 by means of a series of supporting screws 33, only one of which is shown, is spaced above the casing 22, and is centrally recessed, at 34, directly above nozzle 17. Extending from said recess through 20 the central portion of the casing are a series of apertures 35, forming restricted passages for the explosive mixture on its way to the inlet manifold.
- 25 In the operation of our improved device the air entering through the inlets 3 and 4 is drawn by the suction produced in the inlet manifold through the central opening of shell 11, and comes into contact with the fuel emerging from the nozzle 17. The heat 30 generated by the annular heating element 25 is communicated in considerable degree to the fuel within the annular chamber 12 of the shell 11 to facilitate the vaporization of the same; the element 25 is most effective 35 in heating the space surrounding the nozzle 17 where the mixing of the hydrocarbon vapor and the air has its inception. The space surrounding said nozzle and the space inclosed between the two casings 22 and 29 40 and the shell 28 constitute in effect the mixing chamber of the carbureter, and it is to be particularly noted that we have insured the thorough heating of this chamber by the combined action of the two heating 45 elements. The mixture formed in this chamber passes through the apertures 35 and through the space between the shell 28 and casing 29 to the manifold; the transfer of heat to said mixture during its passage 50 through the restricted openings of the second heating element renders the commingling of the constituents still more thorough and insures the entrance of said mixture to the cylinders of the engine at a

proper temperature and in a readily combustible condition. When the suction on the carbureter is increased beyond a certain predetermined point, additional air is obtainable through the openings 10, heretofore referred to. A flat ring 36 is seated on the ring 9 and is free to move vertically with respect thereto, being guided on the screw posts 37 secured to the ring 9. Ring 36 is provided with a plurality of openings, not shown, which are out of register with the openings 10. When the increased suction is sufficient to lift the ring 36, air will pass through said openings to the space surrounding the shell 28 and the two heating elements, and in its passage will become heated by both heating elements.

The air thus admitted becomes a part of the explosive mixture which has already passed through the restricted openings of the second heating element, and by reason of being heated, this air does not chill the mixture so as to render its explosion less efficient.

We claim,

1. In a carbureter, a mixing chamber for hydrocarbon and air, heating devices disposed within said chamber, one at the inlet to and another at the outlet from said chamber, and means for supporting one of said devices in spaced relation to the wall of said chamber, to permit the passage of gases around said heating device.

2. In a carbureter, a mixing chamber providing an air inlet and a hydrocarbon inlet, an electric heating element disposed within and conforming to the wall of said chamber and surrounding both of said inlets, and another electric heating element disposed within said chamber above the first heating element, and supporting in spaced relation to the wall of said chamber, said last named heating element providing a passage therethrough for the gases in said chamber.

3. In a carbureter, a mixing chamber providing an air inlet and a hydrocarbon inlet, a heating element disposed within said chamber and surrounding both of said inlets, an air passage surrounding said mixing chamber and said heating element, and a second heating element disposed within said chamber and providing an outlet from said mixing chamber into said air passage.

4. In a carbureter, means for forming a mixture of air and fuel, a heating element adapted to transfer heat to the constituents of said mixture, a second heating element having a restricted opening therethrough for the passage of said mixture, and means for supplying additional air to said mixture after its passage beyond the second heating means, comprising a passage heated by both of said heating elements.

5. In a carbureter, a mixing chamber, an electric heating element disposed within and surrounding the passage provided by said chamber, a shell inclosing said heating element, and forming the wall of said chamber, and a second electric heating element supported by said shell, above said first element,

said second element providing an interior passage for the gases leaving said chamber.
